UNITED STATES PATENT OFFICE.

EDOUARD C. F. OTTO, OF PECKHAM, COUNTY OF SURREY, ENGLAND.

BICYCLE.

SPECIFICATION forming part of Letters Patent No. 243,959, dated July 5, 1881.

Application filed June 10, 1880. (Model.) Patented in England March 31, 1879.

To all whom it may concern:

Be it known that I, EDOUARD CARL FRIEDRICH OTTO, of Peckham, in the county of Surrey, England, have invented new and useful 5 Improvements in Bicycles, of which the following is a specification.

This invention has for its object improvements in that class of bicycles wherein the rider is seated between two wheels placed one 10 at each end of an axle.

Such improvements relate, first, to an improved arrangement of the seat, whereby smaller wheels may be employed and the entire vehicle made lighter and easier to ride; second, 15 to an improved arrangement of steering-gear, whereby the driving-wheels are more easily converted into steering-wheels, and vice versa; third, to an improved treadle arrangement, whereby the rider can easily maintain his equilibrium on the roughest roads; fourth, to an 20 improved arrangement for applying the brakes.

I will now, with the aid of the accompanying drawings, wherein similar letters of reference indicate corresponding parts, proceed 25 to particularly describe my said invention.

In the drawings, Figure 1 is a side elevation of my improved bicycle. Fig. 2 is a front elevation thereof. Fig. 3 is a plan view. Fig. 4 is a section on line A B, Fig. 3. Figs. 5, 6, 30 and 7 are detail views of the sliding bearings for the propelling crank-shaft.

To carry out my improvements I employ either a straight, rectangular, or curvilinear axle, $g g'$, provided with suitable wheels, a , 35 having india-rubber tires b . Either at or above the horizontal, and somewhat in rear of the vertical, center lines of such wheels I place an adjustable seat, $j j'$, which may be raised or lowered by a bolt and nuts, j^5 , while to prevent 40 jolting suitable springs, $j^2 j^3 j^4$, are conveniently placed beneath the seat. The seat is in this instance mounted on one end of a C-spring, (one or more,) the other end of which is adjustably secured a little above the axle by the 45 bolt and nuts j^5 , as shown. Pivoted to the upper end of this spring is a screw-threaded rod, the lower end of which, after passing through a hole in the lower end of said spring, is provided with a nut. By screwing this nut up on 50 the rod the front side of the seat will be depressed, and by unscrewing said nut the front

side of the seat will be carried upward by the action of its spring. The front side of the seat may be supported by a spiral spring, j' , encircling this screwed rod. By the above-described means the seat can be adjusted to any desired 55 inclination. Duplicate springs, placed side by side, may be employed, if necessary.

By arranging the seat in the rear of the vertical and at about the horizontal center of the 60 wheels not only can lighter and smaller wheels be used and the entire machine rendered lighter, but the rider's equilibrium is readily maintained, owing to sufficient weight being displaced toward the rear to counteract the weight 65 requisite in front on treadles q to propel the bicycle.

To further assist the rider to maintain his balance, treadle-straps q' are fastened to the treadles, wherewith he can raise the crank-shaft and its connections, so as to enable him 70 to pass more easily and safely over obstructions while applying a continuous rotary motion to the treadles. Such treadle-straps greatly assist the rider in applying the brakes, as he 75 can, by raising the crank-shaft, counteract the tendency of the bicycle to throw him forward when the brakes are applied. These straps are so arranged that the rider can withdraw his feet therefrom with perfect ease. 80

Secured to the wheels in any convenient manner and position are pulleys c , which are driven by belts l^2 .

Firmly secured to the axle, and forming in connection therewith a bifurcated frame, are 85 rods k , preferably of the form shown, one near each wheel.

At the lower ends of the rods k , and adapted to slide up and down thereon, are boxes r , in which the respective ends of the crank-shaft t 90 are journaled. The ends of the crank-shaft t project sufficiently beyond the boxes r to receive the driving-pulleys p , which are keyed or otherwise firmly secured thereon, and transmit motion to driven pulleys e by means of 95 belts l^2 , heretofore mentioned. Spiral springs o encircle the lower ends of rods k , the lower ends of said springs abutting against the boxes r and their upper ends against sleeves n , which are adjustably secured on rods k by means of 100 set-screws m^3 . The pressure of these springs on sliding boxes r keep belts l^2 at the proper

tautness. Owing to the belts l^2 connecting driving-pulleys p with driven pulleys c , the rider is prevented from swaying to and fro, and thus materially assisted in maintaining a steady 5 equilibrium, as when he has fixed himself in position the motion of the treadles, which in the absence of the belts would cause a swaying of the bifurcated frame, is counteracted by said belts, which, transmitting motion to the 10 wheels, propel the vehicle, and the swaying motion of the rider is thus converted into the backward or forward travel of the bicycle.

To further illustrate the balancing-power of the machine, let us assume that the rider has 15 placed too much weight on the forward treadle, thus losing his balance. He has then only to lift the hinder treadle with his foot, when he at once transfers the requisite weight to the seat and re-establishes his equilibrium. Moreover, in order, when going uphill, to overcome 20 the inclination of the crank-shaft to rise (induced by the increased resistance to forward travel,) the rider, by assuming a more upright position, can place sufficient weight thereon to 25 keep it at a proper level, while by leaning backward when going downhill (sufficiently, if necessary, to depress the supplementary brake or drag presently described) he can at once counteract any tendency to fall forward.

30 The sliding boxes r are provided with holes u , v , and w , for the reception of the crank-shaft, rod k , and steering-rods k^2 , respectively. The holes v are slightly ovalized at the ends to admit of rocking on rod k when the opposite box 35 and end of the crank-shaft are raised in steering the machine. To these boxes r are attached steering-rods k^2 , formed in two sections, which are connected by tubular nuts k' , provided with right and left screw-threads, so 40 that by turning said nuts one way or the other said steering-rods can be lengthened or shortened. The upper tapered ends of these nuts k' are split and threaded externally to receive lock-nuts k^4 , which prevent them from turning accidentally. These rods k^2 are at their upper ends pivoted to the hubs of steering-levers e , which levers are mounted to oscillate on 45 axles g at points in line with the axial center of the drive-wheels a . By drawing these levers 50 backward the steering-rods k^2 connected therewith will operate to lift the sliding boxes r , and with them the crank-shaft t and driving-pulleys p , thus slackening the belts l^2 . Upon 55 releasing the levers e , they, together with the crank-shaft and its connections, will be caused to again resume their normal positions by the action of springs o on sliding boxes r .

Suitable brakes, l , firmly attached to sliding 60 brake-blocks l^3 , are placed under the driven pulleys c . These brake-blocks l^3 are mounted to slide on rods k , and are connected by wires s to disks d , mounted on the axles g in close proximity to steering-levers e , by which they are operated, and are also connected by wires s' 65 to brake-levers f , which latter are placed in any convenient position, and held therein by springs f' acting on shoulders f'' .

Handles are fitted loosely on the levers e , and are provided near their lower ends with short arms, which, when the handles are twisted in 70 the proper direction, engage and force backward pins projecting upward from disks d , to which the wires s are attached, and draw brakes l up against driven pulleys c .

To change the direction of the machine, one 75 of the steering-levers is drawn backward, which movement slackens the belt l^2 on that side of the machine through the agency of steering-rod k^2 and box r , and at the same time applies the brake with more or less force 80 through the agency of disk d and wire s . The belt l^2 on the opposite side of the machine being kept taut meanwhile, it will be readily seen that the direction of the machine will be 85 changed at once, because at one side the propelling-power is still continued, while on the other side, the belt being slackened, the propelling-power is suspended and the brake is applied with more or less force. In this manner the wheels a are made to serve both as 90 driving and steering wheels.

Should it be found that the steering-lever does not apply the brake with sufficient force, the brake-lever f can be operated in connection therewith.

95 Owing to the brakes being mounted on the bifurcated frame of the machine, there is a tendency, when the brakes are applied, for said bifurcated frame to be carried round with the wheels, which action would result in throwing the rider forward. This tendency is counteracted in some measure by the position and operation of the brake-levers f . These levers require to be drawn upward by the rider, whose entire weight can be thus thrown on the seat, 105 or, in other words, to the rear of the pivotal center of the bifurcated frame.

110 Should the brake l be found insufficient to check the machine when descending steep grades, the rider is enabled, by leaning backward sufficiently, to bring a supplementary brake or drag in contact with the ground. This supplementary brake or drag consists of a back-stay, h , secured to the axle beneath the seat, said back-stay projecting to the rear and 115 downward, and being provided at its end with a small wheel or roller, h^2 , which normally is some little distance above the ground. A luggage-support, h' , may be secured to the back-stay, as shown.

120 Springs s^2 and s^3 are interposed between the lug of brake-block l^3 and the securing-nuts of brake-wires s and s' , so that the brakes are applied with a cushioning action.

125 Springs s^5 , mounted on rods k above the brake-blocks, serve to keep the brakes normally free from contact with pulleys c .

130 Guides m' , secured in lugs m on sleeves n , are used to keep the driving-belts in proper position when slackened.

Having thus described my invention, what I claim as new is—

1. In a bicycle of the character described, the seat arranged at or about the horizontal

and in rear of the vertical center of the wheels, substantially as before set forth.

2. The combination, substantially as before set forth, of the seat, the supporting-spring thereof, and the bolt and nuts for adjusting the seat vertically.

3. The combination, substantially as before set forth, of the seat, the supporting-spring thereof, and the bolt and nut for changing the 10 inclination of the seat.

4. The sectional steering-rods, substantially as before set forth, adapted to be lengthened or shortened.

5. The combination, substantially as before 15 set forth, of the brake-block and the two reversely-acting levers adapted to apply the brake separately or conjointly.

6. The combination, substantially as before set forth, of the rods for applying the brakes, 20 the brake-blocks, and the springs.

7. The combination, substantially as before set forth, of the rods *k*, the brake-blocks mounted to slide thereon, and the springs for keep-

ing the brake-blocks normally in their lower-most positions.

8. The combination, substantially as before set forth, of the driving-pulleys, the driven pulleys, the belts, means for slackening the belts, and the guides.

9. The combination, substantially as before 30 set forth, of the rods *k*, the sleeves adjustably secured thereon, the boxes mounted to slide on said rods below the sleeves, the springs interposed between the sliding boxes and the sleeves, and the belts.

10. The combination, substantially as before set forth, of the crank-shaft mounted to turn in sliding boxes, and means for adjusting said crank-shaft with relation to the seat.

EDOUARD CARL FRIEDRICH OTTO.
